UNITED STATES PATENT OFFICE.

WILLIAM H. GARLOCK, OF SEATTLE, WASHINGTON.

POLISHING-MACHINE.

1,168,189.

Specification of Letters Patent. Patented Jan. 11, 1916.

Application filed May 7, 1914. Serial No. 836,983.

To all whom it may concern:

Be it known that I, WILLIAM H. GARLOCK, a citizen of the United States, residing at Seattle, in the county of King and State 5 of Washington, have invented certain new and useful Improvements in Polishing-Machines, of which the following is a specification.

This invention relates to new and useful 10 improvements in polishing machines, and has for its object the provision of a portable polisher which is adapted to be used on metallic and other signs.

Another object of the invention is the 15 provision of a novel method of supporting the polishing wheel, in connection with the operating means therefor.

Still another object of the invention is the provision of such a device which may 20 be easily and quickly adjusted to the person of the user and conveniently held in operative position.

With the above and other objects in view, I will now proceed to describe my invention in the following specification and accompanying drawings, in which,

Figure 1 is a side view of my improved polishing device, with a part of the handle broken away, and Fig. 2 is a face view of 30 my improved polisher showing the buffing wheel and guide wheel in section.

Referring to the drawings by characters of reference 1 indicates the handle portion of my improved polishing device having 35 formed at the lower end thereof, the gripping member 2. The handle portion 1 is preferably tapered, as clearly illustrated in the drawings, and is provided near its upper extremity with the transverse apertures 3, through which the arms of the U-shaped member 4 are adapted to extend. Each of the arms of the U-shaped member 4 are provided with the shoulders 5, which are adapted to abut the body portion immediately 40 adjacent the aperture 3 when the device is in place. The ends of the U-shaped member are preferably provided with suitable external screw threads which are adapted to coact with the nut 6 in holding the device 50 in position.

Suitably secured adjacent the upper end of the handle portion I preferably provide the electric motor 7, having the axle 8 extended, as clearly illustrated in Fig. 2, and 55 provided with the collar 9. A suitable buffing wheel 10 which is formed of any suit-

able material is secured to the axle and adapted to abut the collar. This buffing wheel 10 is secured intermediate the collar and a suitable nut 11, which is threaded on 60 the end of the extension. An electric current is furnished through any suitable source of supply and is connected through the medium of the switch 12 and the wires 13 with the motor. This switch 12 is secured to the handle portion 1 in any suitable manner and within easy reach of the operator. Thus, it will be seen that the operation of the motor may be controlled without causing undue inconvenience.

A suitable guide wheel 16 is provided and located on the shaft 8, between the collar 9 and the motor 7. This guard wheel is to prevent the fabric portion of the buffing wheel 10 from breaking down while being passed over the surface of the object to be polished and to assist the operator in supporting the device while in operation. This guard wheel 16 is to operate pivotally 70 on the shaft 8 and independent of the buffing wheel 10.

A suitable ring 13 is provided and surrounds the bight portion of the U-shaped member 4. This ring is adapted to form a means by which the strap 14 may be secured to the U-shaped member and through the medium of the snap hook 15 it will be obvious that the said strap may be attached or detached at the will of the operator.

It will be clearly seen from the foregoing 90 that when it is desired to make use of my improved buffing device, the same is carried to the point where it is desired to be used. Upon connecting the switch with any suitable spark supply it will be apparent at the 95 will of the operator the current may be thrown on, which will cause the motor to be set in motion, thereby driving the axle 8, and revolving the polishing wheel 10. Upon placing the strap 14 over the shoulders of 100 the user and grasping the gripping member 2 it will be apparent that the buffing wheel may be directed to adjust the object which is to be polished and through the action of the motor the desired result may be attained 105 in an easy and quick manner, without the necessity of removing the object from its position.

While in the foregoing I have shown and described the preferred embodiment of the 110 invention, I wish it to be understood that I may change the specific combination and

arrangement of parts without in any way departing from the spirit and scope of my invention as defined in the appended claim.

What is claimed is:—

5. A polishing machine of the character described, a support having its sides tapered from the top to the lower portion thereof, and provided with a gripping member at the lower end, a motor fixed to the wider end of the support, a buffing wheel connected on the motor shaft and arranged to be driven thereby, an independently rotatable guard wheel mounted on the motor shaft

intermediate the motor and the buffing wheel, and a U-shaped member extending through the support between the motor and the lower gripping member, to form a hand grip, said grip allowing the pressure of the buffing wheel against the article being polished to be regulated.

In testimony whereof I affix my signature in presence of two witnesses.

WILLIAM H. GARLOCK.
